UNITED STATES PATENT OFFICE.

THOMAS MIDGLEY, SR., OF COLUMBUS, OHIO.

ART OF MANUFACTURING COLLAPSIBLE CORES.

1,284,414.

Specification of Letters Patent. Patented Nov. 12, 1918.

Application filed March 7, 1917. Serial No. 153,145.

To all whom it may concern:

Be it known that I, THOMAS MIDGLEY, Sr., a citizen of the United States, residing at Columbus, in the county of Franklin and 5 State of Ohio, have invented certain new and useful Improvements in the Art of Manufacturing Collapsible Cores, of which the following is a specification.

This invention relates to the art of manufacturing collapsible cores and which cores are designed for use in the manufacture of pneumatic tire casings, preferably inextensible edged casings.

The main object of this invention resides in the method of constructing these collapsible cores wherein the face plates for the ends of the abutting sections forming the annulus are securely fastened to the core sections and bonded in such manner as to 20 make a perfect joint both between the face plates and the core ends and between the face plates themselves. This method is primarily for use where the facings for the ends of the core sections are placed in the 25 imprint and attached to the ends by casting the sections thereon. By constructing the cores in this manner, considerable difficulty has arisen in making the bond between the face plates and the core sections so that a 30 perfect joint is formed, which will not require plugging after the core itself has been finished. My improved method for overcoming this consists in enlarging the imprint at the point in the mold where these end 35 plates are placed prior to the casting operation, so that a surplus of metal is formed at this point. Inasmuch as practically all imperfections in casting occur within the surface, such as blow holes or sand holes, these 40 imperfections can be removed during the finishing process of the core and thus a perfect joint between the face plates and the core sections, is formed.

A further object of my invention resides 45 in a method for preventing the admission of any molten metal between the separable members of the abutting face plates during the casting operation. When this metal is in a highly heated state, it readily finds its 50 way through all openings or crevices and to this end, I provide a plurality of plates sufficient for each set, which are larger than the finished core and arrange these plates in sets and after arranging these plates in sets, 55 I seal the edges of them together to com-

pletely guard against the admission of the molten metal between them and after the casting operation, remove this surplus metal and face plates which latter forms a part of the finishing operation.

Still a further object of my invention resides in a method whereby the means for holding the various core sections in their assembled relation, is cast into position during the casting operation, thus eliminating 65 all machine work as regards this feature.

In the accompanying sheets of drawings, I have shown a completed core constructed in accordance with my improved methods of manufacture and also have attempted to 70 show the relative positions of certain of the parts within the mold imprint prior to the casting operation. In these several views, similar characters of reference designate 75 corresponding parts, and

Figure 1 represents a completed core partially shown in side elevation and partially shown in section,

Fig. 2 is an end view of one of the core sections after the core has been completed. 80 as represented approximately on line 2—2 of Fig. 1,

Fig. 3 is a top view showing the plates forming one set in their proper position within the lower half or drag of the mold 85 box,

Fig. 4 is a cross section taken through line 5—5 of Fig. 4, and,

Fig. 5 shows the relative positions of the face plates and drag and the shape to which 90 the imprint is formed as represented approximately on line 6—6 of Fig. 3.

The present core when finished, is formed of a plurality of sections 1 and 2 sufficient 95 in number to form an annulus, over which the tire may be built. The abutting ends of the sections 1 and 2, as shown, are of general Z - shape, the leg portions being designated generally by the reference numerals 3 and 4 and the intermediate portion by the reference numeral 5. These abutting ends are preferably faced with face plates such as shown at 6. I have shown four plates 6, as comprising each set, two plates of each set being riveted 100 or spot welded together and the outside plates of each pair being stamped out as is shown at 7, so that these face plates may be rigidly attached to the core segments during the process of casting, by placing the as- 105

sembled plates in their proper relation in the mold imprint. These plates 6 are provided with concaved portions 8, so that a tongue and groove structure is provided for 5 the ends of the abutting sections to prevent sidewise or lateral play. Further, the intermediate portions 5 of these plates are preferably shaped to present an offset 9, the offset, as shown, being in a direction toward 10 the outer periphery of the annulus as a whole. This latter construction is provided to relieve circumferential strain when pressure is applied to the sides of the tire casing before and during the time it is 15 cured, when this pressure is applied directly to the sides, the natural tendency of this core is to expand and to do this, there must be separation between the abutting ends of the core section. To overcome this, I have provided 20 the offset portion 9 to relieve the circumferential strain and I prevent direct separation between the core sections by means of the bolt and nut structure to be presently described.

25 In forming the various division plates or sets, I form each set of a plurality of plates which are larger than the finished core, but which are smaller than the corresponding portion of the imprint and arrange these 30 plates in sets. After sealing the edges of these sets to guard against the admission of molten metal between them, I place them in the imprint, and because of the enlargement, the metal is permitted to flow from one section 35 to another and in so doing, covers the sealed edges to form a bead at this point. The core, just after casting is a complete one piece annulus and remains such until the surplus metal allowed for finishing purposes 40 and the surplus metal constituting the bead around the face plates, is removed. On Sheet 2, the various plates 6 are shown as previously described, the outside plates for each set of four being stamped out as shown 45 at 7, to form the means of connection between the cast core sections and the plates themselves. The two inner plates 6 are not attached to each other, but each of these inner plates is rigidly attached to one of the 50 outer plates. Both the inner and outer plates are slightly larger than it is intended the finished core shall be, which has been represented by the dotted finish line 10. The lower half of the mold or the drag portion 55 is represented by the reference numeral 11 and the pattern for the core forms the properly shaped imprint 12 therein. At the point where the face plates occur, this imprint is enlarged as shown at 13, so that a bead of 60 cast metal will be formed at a point where each of these face plates occur. Also, this imprint is slightly tapered away, as shown at 14, to permit the free flow of metal from one section to another during the casting 65 operation. By means of these enlargements, any sand which is collected by the metal during the time it is running through the mold, will collect therein to prevent sand holes in the finished article. Also, there being a considerable surplus of metal at the 7 point where the face plates occur, the metal at the finish level of the core, is not chilled readily when being poured in the mold and consequently, a greater time is allowed for 8 it to shape itself or set in connection with the face plates. Where this metal is rapidly chilled, it does not flow as freely as it should and in this way oftentimes prevents the formation of a perfect bond. By my improved method as outlined, this is overcome.

As has been related, each set of plates constitutes four individual plates, as shown, and the inner plates 6 are slightly smaller in size than the outer plates. After the set has been assembled, the space 15 formed between 9 the two outer plates is filled with some sealing material such as core sand. After this, a channel-shaped structure 16 is clamped into position, which additionally seals the edges of each set to prevent the admission 9 of molten metal between them. This channel structure extends throughout the periphery of each set which is exposed to contact with the molten metal when it is poured as is shown, and the ends of the channels 9 are extended as shown at 17 and additionally secured together by a ring 18. This ring and these extensions serve the purpose of supporting one end of the face plates in the imprint as is shown by reference to Sheet 2. 1 The opposite end of the assembled plates, 10 removably carries a supporting element 19, which latter is provided with a tongue 20 of a size to tightly fit the space 15 formed at the rear end of each set due to the inner 11 plates being of a slightly smaller size than the outer plates. The tongue of this supporting element 19 enters this space and, therefore, forms the means of supporting the rear end of the face plates in the imprint. 12 By this arrangement, it will be apparent that admission of molten metal between the plate sections to cause their fusing together is impossible and also by means of the enlargements 13 and 14, sufficient metal is cast 13 around this portion of the core to form a perfect joint.

In order to eliminate all machine work as regards the means for holding the core sections in their assembled relation, each of 14 the plates constituting the division set, is apertured as shown at 21 and on one side of the set there is placed a bushing or nut 22. On the opposite side there is located a thimble 23, both the thimble and the nut being of a size to correspond with the apertures 21 and to receive the temporary bolt 24. After the thimble and nut have been assembled as is shown, the bolt 24 is screwed into position as is shown, its head 25 engag- 15

ing the thimble 23 to wedge it against one of the outer plates and the threads on the shank of the bolt 24 engaging the threads within the nut to wedge it into contact with 5 the opposite outside plate. The imprint is also suitably formed to receive the head 25 of the bolt as is shown on Sheet 2 and in this manner a third point of support for the assembled division plates within the imprint, 10 is formed. The end of the nut 22 is filled with core sand, or some other sealing medium, as shown at 26 and thus, when the core is cast, the metal forming the various sections flows about the thimble and the nut so 15 that these two are bonded or securely held in position after the metal cools. Further, these members are in proper alignment with each other to properly hold the core in its 20 assembled relation. After casting, the temporary bolt 24 can, of course, be removed and a higher grade bolt inserted. Inasmuch as the thimble and nut are securely drawn toward each other when the plates are placed in the mold, the joint formed between the 25 separable portions of the division plates can also be made perfect.

From the foregoing description, it will appear that I have provided a method wherein a perfect union between the face 30 plates and the cast sections may be had. This is effected by enlarging the imprint as shown at 13 and 14 to provide a surplus of material at this point during the casting operation. The molten metal is prevented 35 from entering the spaces between the face plates because of their sealed edges as related. Finally, the core sections are provided with means for holding them in their assembled relation because of the thimble 23, 40 nut 22 and bolt 24. After the core has been cast, it is machined to a finish along approximately the line shown at 10, which finishing operation removes the surplus plates 45 and also the surplus cast metal. The sealing channel 16 comes off in this finishing operation and after this, removal of the bolts 24 permits the core sections to be separated.

What I claim is:

1. The method of constructing collapsible 50 cores wherein the facings for the ends of the core sections are placed in the imprint and attached to said ends by casting the sections thereonto which consists in enlarging the imprint at the place where said 55 plates occur, casting, and then finishing by removing the surplus cast metal and plates.

2. The method of constructing collapsible cores wherein the facings for the ends of the core sections are placed in the imprint and attached to said ends by casting the sections thereonto which consists in selecting plates which are larger than the finished core, arranging them in sets and placing them in the imprint, enlarging the imprint 10 at the place where said plates occur so that

a bead will be formed over the edges of the plates, casting, and then finishing by removing the surplus cast metal and plates.

3. The method of constructing collapsible cores wherein the facings for the ends of the core sections are placed in the imprint and attached to said ends by casting the sections thereonto which consists in selecting plates larger than the finished core and arranging said plates in sets, sealing the 70 edges of said plates to preclude entrance of molten metal between them, supporting said sets in the imprint so that the molten metal flows from one section to another and covers the sealed edges of said sets, casting, and 75 then removing the surplus cast metal and plates.

4. The method of constructing division plate sets for collapsible cores which consists in forming a plurality of plates for 85 each set to a size larger than the finished core but smaller than the corresponding portions of the imprint, arranging said plates in sets, and sealing the edges of said sets together to guard against the admission of 90 molten metal between them.

5. The method of constructing division plate sets for collapsible cores which consists in forming a plurality of plates for each set to a size larger than the finished 95 core but smaller than the corresponding portions of the imprint, the inner abutting plates being smaller than the outer plates, filling the space thus formed between the outer plates with a sealing medium, and 100 then clamping a metal strip around the edge of each set of plates to additionally guard against the admission of molten metal between them.

6. The method of constructing collapsible 105 cores which consists in assembling a plurality of end plates arranged in a set before casting to form face plates for abutting sections, placing such set in the imprint and supporting a bolt and nut on opposite sides 110 of said set so that the retaining means for holding the abutting sections together are fastened into proper aligning position during the casting operation.

7. The method of constructing collapsible 115 cores which consists in assembling a plurality of end plates arranged in a set before casting to form face plates for the abutting sections, supporting a nut on one side and a thimble on the other side of said 120 set in alignment with each other, placing said set, nut and thimble in an imprint, and then casting.

8. The method of constructing collapsible cores which consists in assembling a plurality of end plates arranged in a set before casting to form face plates for the abutting sections, supporting a nut on one side and a thimble on the other side of said set in 125 alignment with each other, by means of a 130

4
bolt passing through the thimble and threaded into said nut, placing said set, nut and thimble in an imprint, and then casting.

9. The method of constructing collapsible cores which consists in assembling a plurality of end plates arranged in a set before casting to form face plates for the abutting sections, supporting a threaded nut from one side of said set so that it will be cast
10 into one core section and supporting means

which form an alining opening with said nut on the other side of said set so that the other core section will have the alining hole formed therein, and then casting.

In testimony whereof I affix my signature in presence of two witnesses.
